DESIGN FOR A VALVE

Ralph G. Carlson, Chicago, Ill., assignor to Crane
Co., Chicago, Ill., a corporation of Illinois

Application January 16, 1941, Serial No. 98,129

Term of patent 14 years

To all whom it may concern:

Be it known that I, Ralph G. Carlson, a citizen of the United States, residing at Chicago, in the county of Cook, State of Illinois, have invented a new, original, and ornamental Design for a Valve, of which the following is a specification, reference being had to the accompanying drawing, forming part thereof.

The figure is a perspective view of a valve showing my new design. The side not shown is identical with the side shown.

I claim:

The ornamental design for a valve, substantially as shown and described.

RALPH G. CARLSON.
